UNITED STATES PATENT OFFICE

JOHN WALKER CHALMERS, OF LONDON, ENGLAND

MACHINE FOR FORMING PAPER, CARDBOARD OR LIKE BLANKS

Application filed March 18, 1929, Serial No. 348,076, and in Great Britain April 5, 1928.

This invention is for improvements in or relating to machines for forming paper, cardboard or like blanks, and more particularly for a device for stripping the cut away portions from the body thereof.

In order to remove the waste portions of a blank automatically, it is usual to provide small pins on the lower cutting roller which are arranged to be forced into the waste material of the blank and carry the same out of engagement with the body of the blank.

When the waste portions are of considerable size it is found that the said pins are not effective as the waste portions catch on the remainder of the blank and slip off the pins.

The present invention comprises means, independent of the forming rollers, for moving a portion of the waste material relatively to the plane of the blank so that the waste portions are automatically freed from the blank.

The invention will be more particularly described with reference to the accompanying drawings in which:

Fig. 1 shows an elevation of a pair of cutting rollers of a blank cutting machine, with the invention applied thereto.

Fig. 2 shows a typical form of blank for which the invention is adapted, and

Fig. 3 shows a plain view of Fig. 1.

Referring to the drawings; the blank is carried along a table 1 by a pusher or the like (not shown) and delivered to the cutting rollers 2 and 3 which are provided with cutters 4 for cutting the hatched portions shown in Fig. 2.

As the blank passes between the rollers, an oscillating wedge shaped member 5 is depressed about its pivot 6 by the cam 7 which is mounted on the bottom roller. This movement causes the wedge member to move forwardly towards the contact line of the cutting rollers and depresses the waste portion 8 (Fig. 2) beneath the plane of the blank. On each

side of the wedge member horizontal plates 9 are fitted on to which the body of the blank passes, and a space 10 is left in between the plates through which the portion 8 of the waste material passes as it is depressed by the oscillating wedge member 5.

The small hatched portions 11 (Fig. 2) are removed by pins 12 in the usual way.

As the rear portion of waste material 13 approaches the wedge member 5 in the opposite direction to the leading portion 8, the action is somewhat different, and in this case the pins 14 in the middle of the lower roller project into the material of the portion 13 and bend the leading edge of the same downwardly out of the plane of the blank, and as this occurs the wedge member 5 slowly rises as the roller 5a runs down towards the lowest portion of the cam to further bend the portion 13 downwardly and strip the same from the main body of the blank.

Thus it will be seen that according to the present invention there is provided means for ensuring that the waste portion of a cut away blank is automatically removed therefrom during the cutting operation.

What I claim as my invention and desire to secure by Letters Patent is:—

1. In a blank forming machine, the combination with a pair of cooperating forming rollers arranged to sever a portion of a blank from the body thereof, of a cam carried by one of said rollers, and means engaging said cam and having a part thereof movable across the path of movement of the blank to engage with and effect removal of the severed portion of the blank from the body thereof.

2. In a blank forming machine, the combination with a pair of cooperating forming rollers arranged to sever a portion of a blank from the body thereof, of a cam carried by one of said rollers, a two armed lever having one arm thereof in operative engagement with said cam and the other arm thereof movable across the path of movement of the blank to engage with and effect removal of the severed portion of the blank from the body thereof.

In testimony whereof I hereunto affix my signature.

JOHN WALKER CHALMERS.
